(57) **CLAIM**

The ornamental design for a trailer hitch guide, as shown and described.

DESCRIPTION

FIG. 1 is a perspective view of the trailer hitch guide showing my new design;

FIG. 2 is a left side view the right side view being a mirror image thereof;

FIG. 3 is a front view thereof;

FIG. 4 is a rear view thereof;

FIG. 5 is a top plan view thereof; and,

FIG. 6 is a bottom plan view thereof.

The broken lines showing the hitch extension for sliding engagement within a receiver coupling are for illustrative purposes only and form no part of the claimed design.
